UNITED STATES PATENT OFFICE.

GEORGE EDWARD CHARRON, OF OTTAWA, ONTARIO, CANADA.

ELECTRICAL SAFETY DEVICE FOR RAILROADS.

1,226,619.

Specification of Letters Patent.

Patented May 15, 1917.

Application filed April 19, 1915. Serial No. 22,506.

To all whom it may concern:

Be it known that I, GEORGE EDWARD CHARRON, a subject of the King of Great Britain, and a resident of the city of Ottawa, in the county of Carleton, Province of Ontario, and Dominion of Canada, have invented certain new and useful Improvements in Electrical Safety Devices for Railroads, of which the following is a specification.

10 My invention relates to improvements in electrical safety device for railroads as described in the present specification and illustrated by the accompanying drawings that form part of the same.

15 The invention relates particularly to means for indicating through an alarm bell or colored light anything wrong with the rail joint, and consists essentially in the combination with a plurality of electric

20 wires, of means secured on the rail and fish plate, whereby on said fish plate being displaced said means contact to complete the circuit and thus operate the indicator or light to give the alarm or signal.

25 The objects of my invention are to provide a new, simple, efficient and inexpensive means for announcing either by an alarm bell, signal or colored light when anything is wrong with the rail joint, such as spreading of the rails or anything that will affect the normal position and condition of the fish plate.

30 A further object is to provide a device of this kind that can be readily fitted on any existing road with most satisfactory results.

35 A still further object is to obviate or prevent derailments by giving notice beforehand, and thus insuring safety to passengers.

With these and other objects in view, 40 which will hereafter be more fully described and claimed, reference is now had to the accompanying drawings in which like letters of reference indicate corresponding parts in each figure, and in which,

45 Figure 1 is a side elevation of my device.

Fig. 2 is an enlarged cross section on line Y—Y of Fig. 1.

Fig. 3 is an enlarged detail side view of the electric connection.

50 Fig. 4 is a cross section on line X—X of Fig. 3.

Fig. 5 is a diagram of the wiring.

Referring to the drawings, A and A¹ are a pair of abutting rails mounted on the

sleepers C and operatively connected in the usual manner by the fish plate B. These rails carry boxes d and d¹ suitably secured thereto, the said boxes being provided at one end with lugs e and i respectively, the other ends of the boxes being open for an object which will be made clear hereafter.

Operatively mounted on the fish plate B are a pair of rods k and g having one end embraced by the hollow boxes d and d¹ respectively. Located below the said boxes is a conduit M housing a plurality of electrical wires which in the embodiment illustrated are four in number, i², k², g² and f¹ respectively, the first and last of which are bridged by the wire l while the wires i² and k² are connected to the opposite terminals of a battery or source of power M.

The wires k² and g² are connected by the wires i² and k¹ to the lug i and rod k carried by the box d and the fish plate B respectively. These wires k² and g² are further connected through the wires f and g¹ to the lug e and the rod g mounted on the box d¹ and the fish plate B, while the wires g² and f¹ are connected to a suitable signal N.

In the operation of the device, should either of the rails A or A¹ become displaced so that either of the rods k or g should be brought into contact with the inner walls of the casings d or d¹ respectively, an electric circuit will be closed including the source of power M, the wire l, the wire f¹, signal N, wire g², wire k¹, rod k, box d, lug i, wire i², wire k², back to the source of power M operating the said signal and indicating that there is something the matter with the rail joint.

In the event of the rod g making contact with the box d¹, a similar circuit is completed comprising the source of power M, the wire i², wire l, wire f¹, signal N, wire g², the wire f, lug e, the box d¹, the rod g, wire g¹, wire k², back to the source of power M, thereby operating the signal N so indicating that there is something the matter with the rail joint.

What I claim for my invention is:

The combination with a rail joint, including a pair of abutting rails and a fish plate, of hollow boxes mounted on the rails and provided at one end with lugs, rods operatively mounted in the fish plate having one end embraced by the hollow boxes, a signal,

a source of power, and means for closing a circuit including the signal, source of power and the said rods and boxes should the rails become displaced.

5 In testimony whereof I have hereunto signed my name in the presence of two subscribing witnesses at the city of Ottawa, in

the county of Carleton and Province of Ontario, this 31 day of December, 1914.

GEORGE EDWARD CHARRON.
